UNITED STATES PATENT OFFICE.

FREDERICK HOWARD AULD, OF COLUMBUS, OHIO.

CONTAINER FOR RAZOR-BLADES.

1.310,407.

Specification of Letters Patent. Patented July 22, 1919.

Application filed December 21, 1918. Serial No. 267,833.

To all whom it may concern:

Be it known that I, FREDERICK HOWARD AULD, a citizen of the United States, residing at Columbus, in the county of Franklin and State of Ohio, have invented a certain new and useful Improvement in Containers for Razor-Blades, of which the following is a specification.

The object of this invention is to provide an improved container designed to receive a package of "safety" razor blades and from which container, when the cover thereof is removed, the package is projected into position to permit the easy abstraction of one or 15 more of the blades.

The invention is embodied in the example herein shown and described, the features of novelty being finally claimed.

In the accompanying drawing—
20 Figure 1 is a top plan view of the container with the cover removed.

Fig. 2 is a sectional view on the line II—II Fig. 1.

Fig. 3 is a view similar to Fig. 2 showing 25 the container containing blades with the cover applied.

Fig. 4 is an end view looking at the left hand end of the container as shown in Fig. 2.

In the several views 5 designates the container proper which is a box-like structure of ordinary elongated rectangular form of about the circumferential dimensions of the razor blades, and having an ordinary rabbet 5^a or seat around its rim for the reception of

30 the cover 11. In one end of the box is soldered or otherwise secured the receptacle for the razor blades, said receptacle consisting of a body or piece preferably of fairly stiff sheet metal 6 cut and bent to form a central tongue 7 projecting upward from the body 6, upwardly extending side flanges 8 having inwardly standing lips or keepers 8^a, and an upwardly bent end 9 having a forwardly bent lip or keeper 10. The spring body 6

40 may be said to constitute a movable bottom for the container. The upwardly bent end 9 affords the portion for attaching the razor receptacle to the end wall of the box 5. The plate 6 is bent to stand at an acute angle to the upwardly standing portion 9 so that when the receptacle is pressed down into the box as by the cover 11 the receptacle tends 45 normally to spring back to the position shown in Fig. 2. The cover, however, has

sufficient frictional engagement with the box 55 to prevent the projection of the razor receptacle until the cover is forcibly removed.

The razor blades are usually each inclosed in a small envelop 12 and a package of these is inserted endwise through the opening into 60 the receptacle under the keepers 8^a and the forwardly bent lip 10 after which the receptacle and the blades are depressed into the box and the cover applied as shown in Fig. 3. The insertion of the package of blades 65 depresses the spring tongue 7 and the resilience of this tongue presses the package upward with the uppermost blade in contact with the keepers 8^a.

When a blade is desired for use it is only 70 necessary to remove the cover 11 whereupon the receptacle is automatically projected from within the box after which the uppermost blade of the package is easily withdrawn from under the keepers 8^a by the 75 proper application of the thumb or finger.

The blade receptacle, it will be observed, has a double resilience, one tending to lift the package out of the box and into position to facilitate the insertion or removal of the 80 blades and the other to hold the blades with a slight frictional resistance against the keepers 8^a so as to permit the easy removal of the uppermost one of them without removing the others. 85

The forms of the parts can be changed without departing from the invention as claimed.

What I claim is:

1. A container for razor blades and the like comprising, in combination, a box-like structure and a movable bottom therefor secured at one wall therein, said bottom consisting of a resilient body provided with a resilient tongue projecting therefrom, and a keeper between which and the resilient tongue the articles are placed.

2. A container for razor blades and the like comprising, in combination a box-like structure and a movable bottom therefor secured at one wall therein, said bottom consisting of a resilient body provided with a resilient tongue projecting upward therefrom, a keeper between which and the resilient tongue the articles are placed and a removable cover for the box-like structure. 105

3. A container for razor blades and the like comprising, in combination a box-like

structure and a movable bottom therefor secured at one wall therein, said bottom consisting of a resilient body provided with a resilient tongue projecting upward therefrom and a keeper carried by the body between which and the resilient tongue the articles are placed.

4. A container for razor blades and the like comprising, in combination a box-like structure and a movable bottom therefor secured at one wall therein, said bottom consisting of a resilient body provided with a resilient tongue projecting upward there-

from, and a keeper between which and the resilient tongue the articles are placed. 15

5. A container for razor blades and the like comprising, in combination, a box-like structure and a movable bottom therefor secured at one end therein, said bottom consisting of a resilient body provided with a keeper at the end secured and a resilient tongue projecting upward from the resilient body and a second keeper between which and the resilient tongue the articles are placed. 20

FREDERICK HOWARD AULD.
